UNITED STATES PATENT OFFICE.

THOMAS J. AUSTIN, OF BELLE PLAIN, TEXAS.

WASHING-MACHINE.

SPECIFICATION forming part of Letters Patent No. 224,321, dated February 10, 1880.

Application filed August 20, 1878.

To all whom it may concern:

Be it known that I, THOMAS J. AUSTIN, of Belle Plain, in the county of Callahan and State of Texas, have invented certain new and useful Improvements in Washing-Machines; and I do hereby declare that the following is a full, clear, and exact description thereof, reference being had to the accompanying drawings, and to letters of reference marked thereon, 10 which form a part of this specification.

My invention relates to the class of washing-machines which employ a circular corrugated or fluted bed with a conical roller revolving about a central post; and my invention consists of certain improvements in the construction and arrangement of the parts, which are fully shown and set forth in the following description and claims.

Figure 1 is a plan of a machine which embodies my invention. Fig. 2 is a vertical central cross-section. Fig. 3 is a horizontal section through the flue B and fire-box E, and Fig. 4 is a front elevation of the fire-box E.

The tub has the central portion, G, of the bottom raised, making a drum having outwardly-sloping sides, and around this drum there is an annular trough, in which the conical roller R travels. The sides A of the tub and the drum G are riveted to upturned flanges on the outer and inner edges, respectively, of the bottom of this annular trough, and the sides A of the tub are extended down around the circular flue B.

The tub has the spout D, provided with a stop-cock for drawing off the water, and it is hinged to the flue B, on which it rests, the hinge being placed under the spout D, and a hasp-fastening is placed on the opposite side.

The flue B is circular in form, extending 40 around the aforesaid annular trough.

E is a fire-box, removably attached to the flue B, and H is a smoke-pipe. The whole is supported on a proper frame, N.

A second or false bottom, made of fluted zinc or copper, is placed in the bottom of the aforesaid annular trough. This is made in two pieces, in order that it may be conveniently taken out and put in.

The zinc bottom is perforated in order that 50 the hot water and steam may readily circulate through it.

The conical roller R is formed of two circular end pieces, the conical surface being made of rungs tenoned into the end pieces. These rungs have open spaces between them, so that the water can pass through. The journal of the roller is fastened to one end of the curved arm X, which arm passes up over the drum G, and is hinged at the other end to the arm L. The arm X has a slot, through which the shaft P passes, while the arm L is clamped to the shaft by a set-screw, K, and has the guides I, between which the arm X plays.

The coiled spring S, encircling the shaft P, is placed between the cog-wheel T and the lever X, and presses down the roller R, producing a firm and uniform pressure, as well as affording the necessary elasticity.

The shaft P passes down through the drum G, and its lower end is supported by an iron brace spanning the bottom of the drum. A nut on the bottom of the shaft retains it in place. The upper end of the shaft is screw-threaded and passes through the coupling-joint U, to which it is secured by a nut on 75 the end of the shaft.

The crank-shaft F is supported by the standard O, to which it is secured by a collar-block and bolts, which standard is fastened to the side of the tub, and the other end of said shaft 80 is supported by the coupling-joint U.

The shaft F carries the small cog-wheel D, which meshes into the larger wheel T on the shaft P.

The shafts, gearing, and roller can all be removed by unfastening the collar-block which fastens the shaft F to the standard O, and removing the nut on the bottom of the shaft P; then they can be lifted out.

The operation of the machine is plain. The clothes are placed in the annular trough formed between the drum and the sides of the tub. The water and suds are heated by the fire below, and the conical roller R is driven round in the trough over the clothes by means of the 95 shafts and gearing, and washes and cleans the clothes.

Having thus described my invention, what I claim as new, and desire to secure by Letters Patent, is—

1. The combination of a washing-machine having an annular trough with the circular

flue B, fire-box E, and stove-pipe H, all substantially as described, and for the purpose set forth.

2. The combination, with a washing-machine having an annular trough, of the conical roller R, arm X, arm L, shaft P, and spring S, with mechanism, substantially as described, for rotating the shaft, all substantially as described, and for the purpose set forth.

10 3. The combination, with a tub having an

annular trough, of the crank-shaft F, shaft P, coupling-joint U, gear-wheels D and T, standard O, spring S, arms X and L, and conical roller, all substantially as described, and for the purpose set forth.

THOMAS J. AUSTIN.
